(57) CLAIM

The ornamental design for a detachable tag for footwear, as shown and described.

DESCRIPTION

FIG. 1 is a front view of a detachable tag for footwear, showing our design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a front view thereof attached to an item of footwear. The broken lines in FIG. 7 depict environment and form no part of the claimed design.

The “Limitless” logo forming part of the claimed design is a registered trademark of I AM Apparel, LLC.

1 Claim, 3 Drawing Sheets
